UNITED STATES PATENT OFFICE.

RAYMOND A. BECKER AND THOMAS E. MADDEX, OF HILLSBORO, ILLINOIS.

INSULATOR-THIMBLE.

1,268,315.

Specification of Letters Patent.

Patented June 4, 1918.

Application filed June 6, 1917. Serial No. 173,162.

To all whom it may concern:

Be it known that we, RAYMOND A. BECKER and THOMAS E. MADDEX, citizens of the United States, and residents of Hillsboro, in the county of Montgomery and State of Illinois, have invented certain new and useful Improvements in Insulator-Thimbles, of which the following is a specification.

The present invention relates to insulators, and more particularly to that type of insulator adapted to be supported upon pins or studs usually carried upon cross-arms and the like, for supporting and insulating line wires of high and low tension.

In prior insulator construction, wooden pins have been employed which are screwed directly into the insulator body. The chief objection found to such a construction has been that in the larger size insulators, such as are used in high-tension transmission, wood pins are unsuitable on account of mechanical weakness. This has been attempted to be overcome by the provision of metallic pins of sufficient strength but they are found unsatisfactory on account of the tendency to cramp the threads and thus injure the body of the insulator. It has also been attempted to overcome the defect by the provision of a metal pin which is cemented directly into the insulator pin hole. This, however, has the disadvantage that in installing, the combined weight of the assembled pin and insulator body is too heavy to be conveniently handled in fixing the pin or stud to the cross-arm or other support employed. Further, objection is also found in this latter type of insulator mounting for the reason that the cement, which is practically unyielding, transmits or communicates to the walls of the insulator body all of the mechanical stresses set up by the expansion and contraction of the metal pin.

Various other attempts have been made to overcome all of these objections, and a further attempt has been embodied in providing a metal thimble which is internally threaded for detachable engagement with a metallic pin or stud, the thimble being cemented into the opening in the insulator body. It is readily seen that while this latter construction admits of the separate mounting of the pin upon the cross-arm or other support, it does not offset the transmission or communication of mechanical

stresses set up by the expansion and contraction of the metal pin and the thimble to the adjacent walls of the insulator body, thus cracking and breaking the latter. There is one instance familiar to the present inventors which embodies the threading of the pin, the threading of a shell over the pin which is made of relatively thin metal, and which has the threads thereof pressed into the body of the shell, and which is cemented in the insulator body. The closed end of the shell is provided with a cork insert adapted to cushion and take up expansion and contraction of the pin longitudinally. However, the transverse or diametrical expansion and contraction of the pin is not provided for, and such resultant stresses of the thimble causes the cracking and breaking of the insulator body.

It is the object of the present invention to overcome all of these defects by providing a novel form of thimble capable of taking up not only the longitudinal mechanical stresses incident to the expansion and contraction of the pin and the thimble, but also the lateral or transverse mechanical stresses, and to provide a thimble which may be easily removed and replaced upon the stud end of the pin, and which may be cemented securely in the insulator body.

The above, and various other objects and advantages of this invention will be in part described, and in part understood, from the following detailed description of the present preferred embodiment, the same being illustrated in the accompanying drawing, 90 wherein:

Figure 1 is a longitudinal section through an insulator provided with a thimble constructed according to the present invention, the thimble being shown in elevation.

Fig. 2 is a longitudinal view, enlarged, of the thimble, disclosed partly in section, and partly in elevation.

Fig. 3 is a transverse section taken substantially on the line 3—3 of Fig. 2, through the insulator thimble, showing the spacing between the inner and outer sections thereof.

Referring to this drawing, 10 designates the body of an insulator which may be formed of a plurality of sections in the usual manner secured together in interfitting relation by films of cement 11, or the like.

In the present embodiment, the thimble

comprises an inner tubular section 12 of metal, or the like, provided with internal screw-threads adapted to receive a supporting pin therein, and admitting of the removal and positioning of the thimble upon the pin by merely screwing and unscrewing the thimble with respect thereto. The base or lower end of the inner section 12 of the thimble is provided with an annular outstanding flange 13 having a relatively flat lower end or base portion adapted to bind against the pin and thus securely hold the thimble from turning upon the pin when the thimble is secured in position. The opposite end of the thimble section 12 is provided with a closure wall 14 which may engage the upper end of the supporting pin or arm.

The thimble is provided with an outer or shell section 15 preferably formed from sheet metal and tubular in shape. The outer section 15 is adapted to fit loosely over the inner section 12 and preferably forms an annular space between the two sections, as shown in Fig. 3. This annular space provides for the transverse expansion and contraction of the inner thimble section 12, and the outer shell section 15 is preferably of slightly greater length than the inner section 12 to provide a space between the closure wall 14 of the inner section and the upper closed section 16 of the outer section.

The outer shell section 15 is preferably corrugated annularly to provide peripheral beads and depressions or grooves arranged alternately from end to end of the shell section 15 for the purpose of absorbing longitudinal and transverse mechanical stresses incident to expansion and contraction of the parts, and also to afford anchoring means adapted to be embedded in the cement 17, or other securing body, adapted to hold the thimble in the opening of the insulator body 10.

The open or base end of the shell section 15 is formed into a flaring flange 18 which is spun or otherwise suitably formed about the marginal edge of the base flange 13 of the inner section 12 for the purpose of firmly uniting the sections 12 and 15 of the thimble. It will be noted that the marginal edge of the flange 18 of the outer section 15 is turned inwardly beneath the base portion 55 of the flange 13 so as to firmly hold the shell section 15 from longitudinal displacement from the inner section 12.

It will be noted that the thimble of this invention comprises inner and outer sections which are spaced apart annularly and longitudinally so that the sections are arranged substantially concentric with respect to each other and the said sections are permitted to expand and contract independently of each other without communi-

cating or transmitting mechanical stresses of either the thimble sections or the pin upon which the thimble is supported, to the body portion 10 of the insulator. In this manner, the pins may be independently secured to the cross-arms or other supports usually employed for the pin, and the insulator bodies 10 with the thimbles cemented or otherwise suitably secured therein may then be placed upon the pins after the latter are mounted. It will also be noted that special threads do not have to be provided in the pins and in the thimble opening, and that the outer shell 15 may be formed from sheet metal, or the like, such as drawn steel, and that the parts are firmly united by spinning or overturning the free end flange of the outer shell about the base flange of the inner section.

It is of course understood that various changes and modifications may be made in the details of construction and design of the above specifically described embodiment of this invention, without departing from the spirit thereof, and being restricted only by the scope of the following claims.

We claim:

1. In an insulator thimble, the combination of an inner cylindrical section having internal threads and an outstanding base flange, and an outer shell section of greater internal diameter than the external diameter of the inner section and provided with a base flange engaging about the base flange of the inner section to hold the sections in concentric spaced-apart relation, said outer section being provided with annular corrugations and being of greater length than the inner section.

2. In an insulator thimble, the combination of an inner section of cylindrical form closed at one end and provided with a base flange at its opposite end, said inner section having internal threads adapted to detachably engage a supporting pin, and an outer section of tubular form fitting over the inner section and provided with a closed end and an outwardly flaring flange at its opposite end adapted to be turned over the base flange of the inner section for uniting said inner and outer sections, the outer section being also provided with annular corrugations extending from end to end of the outer section to provide peripheral beads adapted to be secured in the opening of an insulator body, and adapted to absorb mechanical stresses transmitted to the thimble by the supporting pin.

3. In an insulator thimble, the combination of a pair of concentric spaced-apart sections, the inner section having internal threads adapted for detachable engagement over a supporting pin, the outer section being provided with annular corrugations forming alternately arranged beads and

grooves extending from end to end of the outer section, and adapted to absorb mechanical stresses incident to the contraction and expansion of the inner section and supporting pin, said sections being closed at one end and the outer section being of greater length than the inner section to accommodate the longitudinal expansion and contraction of the sections, and said sections being provided at their opposite ends with ¹⁰ interlocking base flanges adapted to unite the same.

RAYMOND A. BECKER.
THOMAS E. MADDEX.
